UNITED STATES PATENT OFFICE.

HENRY BROCKMEYER, OF IRVING, KANSAS.

DISK-SUPPORTING ARM.

1,035,776.

Specification of Letters Patent. Patented Aug. 13, 1912.

Application filed December 27, 1911. Serial No. 668,075.

To all whom it may concern:

Be it known that I, HENRY BROCKMEYER, a citizen of the United States, residing at Irving, in the county of Marshall and State 5 of Kansas, have invented new and useful Improvements in Disk-Supporting Arms, of which the following is a specification.

The invention relates to supporting arms, and more particularly to the class of disk 10 supporting arms for cultivators or the like.

The primary object of the invention is the provision of a supporting arm of this character in which the disk may be angularly adjusted and the arm removed from the cultivator frame, when desired, the arm being capable of adjustment, and may be securely fastened to such cultivator frame.

Another object of the invention is the provision of an arm of this character in which 20 the cultivator disks may be set level and all have the same angle to the dirt, and also that will permit the setting of the disks to throw dirt away from the growing plants or up to the same, as may be required.

25 A further object of the invention is the provision of a supporting arm which is simple in construction, and that may be mounted upon varying sized cultivators, without altering the parts thereof or reconstructing 30 the same, the arm being strong, durable, and inexpensive in manufacture.

With these and other objects in view, the invention consists in the construction, combination and arrangement of parts, as will 35 be hereinafter more fully described, illustrated in the accompanying drawings, and pointed out in the claims hereunto appended.

In the drawings: Figure 1 is a top plan view of a wheeled cultivator, showing the 40 disk supporting arm constructed in accordance with the invention applied thereto. Fig. 2 is an enlarged side elevation of one of the disk supporting arms. Fig. 3 is an enlarged vertical longitudinal sectional view 45 through the same. Fig. 4 is an end elevation of the arm with the disk removed. Fig. 5 is a similar view, looking toward the opposite end. Fig. 6 is a plan view of the clutch surface on one section of the arm. Fig. 7 is 50 a similar view of the clutch surface on the other section of the arm. Fig. 8 is a sectional view on the line 8-8 of Fig. 2. Fig. 9 is a side elevation of a slightly modified form of disk supporting arm. Fig. 10 is a 55 vertical longitudinal sectional view through the same. Fig. 11 is a sectional view on the line 11 of Fig. 9. Fig. 12 is a side elevation

of a further modification of the disk supporting arm. Fig. 13 is a longitudinal sectional view therethrough. Fig. 14 is an end elevation of the arm. Fig. 15 is an end elevation of one section of the arm, showing the clutch surface thereon. Fig. 16 is an end elevation of the other section of the arm, showing the clutch surface. Fig. 17 is a sectional view on the line x-x of Fig. 14. Fig. 18 is an end view of the arm showing the clutch surface thereon. Fig. 19 is a similar view of the companion clutch surface for engagement therewith.

Similar reference characters indicate corresponding parts throughout the several views of the drawings.

Referring to the drawings by numerals, the cultivator comprises a rectangular 75 frame 10, secured at its forward end to a tongue 11, whereby the machine is drawn forwardly, the rear end of the tongue being provided with a right angular plate 12, to which the rear end of the frame is secured. Secured to the opposite sides of the frame is a pair of hangers 13 which are provided with bearings 14 for the reception of two rocking bars 15 and 16, respectively.

80 Adjustably secured to the bar 15 is a pair 85 of beams 17, the same carrying the usual shovels 18. Each of the bars 15 and 16 is of squared formation in cross section throughout its length, and to the bar 16 is adapted to be connected the disk support- 90 ing arm, presently described.

Carried by the frame 10 is a substantially U-shaped crank axle 19, on the spindle ends 20 of which are mounted the usual ground 95 wheels 21 for the supporting of the frame and permitting the travel thereof over the ground.

Each of the disk supporting arms comprises a casting forming a limb 22, the same being slightly downwardly arched to give 100 the proper curvature thereto, and formed in the upper edge thereof, intermediate its ends, is a recess 23, the limb 22 being formed with a longitudinal bore 24 intersecting the said recess 23, the said bore at the inner end 105 of the limb 22 opening into a pocket 25, in which is slidably fitted a forked block 26, the same being formed with a stem or rod extension 27 passed through the bore and protruding in the recess 23, the protruded 110 end of the stem or rod extension being provided with a right hand thread 28 which is engaged by a turn-buckle 29. Slidably fitted in the bore opening through the outer

end of the limb 22 is a stem or rod extension 30, the inner end of which is provided with a left hand thread 31 engaging the turn buckle 29, which latter is located with-
5 in the recess 23 in the limb.

Formed on the outer end of the limb 22, concentrically about the bore therein, is a clutch surface 32 which is designed to engage with a similar clutch surface 33 formed on the inner end of an adjustable sleeve or cap section 34, in which is mounted a slideable forked block 35 formed on the outer end of the stem or rod extension 30, the sleeve or cap 34 being formed with a
10 groove 36, the inner face of which is pro-
vided with a plurality of parallel clamping ribs 37, and in this groove 36 is disposed a spool-like turning knuckle 38, the same being rotatably journaled upon a bolt member 39
15 engaged in the forked end of the slideable block, the said turning knuckle being formed with a plurality of clamping ribs 40 on its outer surface to engage with the clamping ribs 37 formed in the groove 36,
20 so that the knuckle may be locked against rotation on the bolt member, in a manner presently described.

Fixed medially in the knuckle 38 and projecting outwardly at right angles thereto is a disk supporting spindle 41, on which is journaled a ground working disk 42 of the usual type, the spindle 41 being provided with an adjustable dirt guard collar 43, as usual. It is evident that the spindle 41 may be angularly adjusted on the turning of the knuckle 38 in the forked block 35 for the proper positioning of the ground working disk 42 journaled upon the spindle.

Fixed in the fork of the slideable block 26
40 mounted in the inner end of the limb 22 is a clamping block 44, the same being formed in its inner face with a V-shaped notch 45, and likewise the inner end of the limb 22 is formed with a V-shaped notch 46 register-
45 ing with the said notch 45, and in these notches is engaged the rocker bar 16 mounted in the hangers depending from the frame of the cultivator. Thus, it will be seen that the disk supporting arm may be readily fas-
50 tened to the rocker bar on the cultivator frame, the clamping block 44 being secured in the fork of the slideable block 26 by means of a detachable bolt member 47 passed through the fork and the said clamping block, as will be obvious.

The adjustable sleeve or cap 34 is cut away at its opposite sides to provide notches 48 which permit the spindle 41 to be swung to either side of the disk supporting arm
60 and at right angles thereto, should it be de-
sired.

For adjustably securing the cap or sleeve 34 to the outer end of the limb 22 and also clamping the latter to the rocker bar 16,
65 it is only necessary to turn the turnbuckle

29 in one direction, which moves the stems or rod extensions 27 and 30 toward each other, so that the clamping block 44 will bind against the rocker bar 16, and the clutch surfaces 32 and 33 on the limb 22 and
70 adjustable cap or sleeve 34, respectively, will lock with each other. Also the knuckle 38 will be moved, so that the clamping ribs 40 thereon will engage the clamping ribs 37 in the groove 36 in the cap or sleeve 34, thus
75 locking the spindle 41 in adjusted position for sustaining the disk 42 journaled upon the spindle 41 in proper angular disposition for the working of the ground on the ad-
vancement of the cultivator.

In Figs. 9, 10 and 11, there is shown a slight modification of disk supporting arm, wherein the limb 49 has passed through the longitudinal bore 50 therein the stems or rods 51 and 52, the inner ends of which are
80 formed with right and left hand threads 53 and 54 which engage in a turn-buckle 55, the stem 51 being formed with a slideable forked block 56 which fits in the pocket 57 in the inner end of the limb 49, in the fork
85 of which is detachably fixed a clamping block 58, the latter and the inner end of the limb being notched for receiving the rocker bar 16, whereby the limb may be securely
90 clamped thereto. Near the outer end of the stem or rod 52 are formed opposed flat faces
95 59 which are intersected by an elongated slot 60 provided in the said stem or rod 52, through which is passed a tapering tubular extension 61 formed on one part 62 of a
100 turning knuckle, the other part 63 thereof being provided with a tapering bore receiving the said tubular extension 61, the said parts of the turning knuckle being disposed
105 on opposite sides of the flattened portion of the stem or rod 52. Passed through the parts 62 and 63 and the tubular extension 61 is a fastening member 64, the same en-
gaging a disk carrying spindle 65 which has its inner end engaged in a loop portion
110 66 of the said fastener, and carried upon the said spindle is the usual ground working disk 67, the inner end of the spindle 65 being engaged in diametrically opposed
115 notches 68 formed in the part 62, so as to prevent the turning of the spindle relative to the knuckle. Slidably fitted on the stem 52 and disposed at opposite sides of the turning knuckle are clutch blocks 69 and 70,
120 respectively, the inner or meeting faces of
125 which are formed with alining grooves 71 receiving the turning knuckle, the said grooves being formed with a plurality of clamping ribs 72 which are adapted to en-
gage or lock with similar clamping ribs 73 formed on the outer surfaces of the parts
130 62 and 63 of the turning knuckle. Detach-
ably threaded on the outer end of the stem 52 is a nut 74, against which is engaged the clutch block 70; while the clutch block 69

on its inner face is formed with a clutch surface 75, the latter being adapted for locking engagement with the clutch surface 76 formed on the outer end of the limb 49. 5 Thus it will be seen that the limb may be readily fastened to the rocker bar 16, and also the spindle supporting and ground working disks may be sustained in angularly adjusted position, the adjustment 10 thereof being permitted by the turn-buckle, as will be obvious.

In Figs. 12 to 17, there is shown a further modification of the disk supporting arm, comprising a limb 77 which is slightly 15 downwardly arched to give the proper curvature thereto, and has formed in the upper edge thereof, intermediate its ends, a recess 78, the said limb being formed with a longitudinal bore 79 intersecting the recess 78, the said bore, at the inner end of the limb, opening into a pocket 80, in which is 20 slidably fitted a forked block, 81, the same being formed with a stem or rod extension 82 passed through the bore and protruding 25 into the recess 78, the protruded end of the stem or rod extension being provided with a right hand thread which is engaged by a turn-buckle 83. Slidably fitted in the bore 79 opening through the outer end of the 30 limb 77 is a stem or rod extension 84, the inner end of which is provided with a left hand thread engaging the turn-buckle 83, while its outer end is fixed in or integral 35 with a fork 85, the inner portion of which is surrounded by means of a block 86, the inner face thereof being formed with a ratchet surface 87 engaging with a corresponding ratchet surface 88 formed on the outer end of the limb 77, the clutch surfaces 40 being designed to engage with each other for locking the block 86 in adjusted position relative to the limb. Carried by the fork 85 and secured thereto by means of a bolt member 89 is a clamping block 90, the adjacent or meeting faces of the blocks 86 and 90 being provided with alining ratchet faced grooves 91 receiving a spool-like turning knuckle 92, the same being formed with a ratchet surface 93 adapted for engagement 45 with the ratchet surface 91 of the grooves in the blocks 86 and 90 for locking the turning knuckle in adjusted position, this being accomplished by turning the buckle 83 for the drawing of the rods or 50 stem extensions 82 and 84 toward each other. The turning knuckle 92 is formed with a longitudinal bore 94, in which is fitted an eye bolt 95, the eye 96 of which receives the disk spindle 97, the stem being 55 provided at its threaded end with a nut 98 for the tightening of the bolt in the turning knuckle, whereby the spindle 97 will be

held fast therewith. One end of the spool-like knuckle is provided with a channel 99 receiving the spindle 97, so as to prevent 65 the turning thereof relative to the knuckle when said spindle is fastened thereto. In the forked block 80 is fixed a clamping block 100, the same being formed in its inner face with a V-shaped notch 101, and 70 likewise the inner end of the limb 77 is formed with a V-shaped notch 102 registering with the notch 101, and in these notches is engaged the rocking bar 16 mounted in the hangers depending from the frame of 75 the cultivator. Thus it will be seen that the supporting arm may be fastened to the rocking bar on the cultivator frame.

From the foregoing, taken in connection with the accompanying drawings, it is 80 thought that the construction and operation of the invention will be readily understood, without requiring a more extended explanation.

What is claimed is:

1. The combination with a cultivator having a rocker bar, of a plurality of disk supporting arms, each comprising a limb having a recess intermediate its ends, stems 85 slidable in the limb and intersecting the recess and having forked extremities, a turn buckle adjustably engaging the stems for connecting the same, a disk journal having a turning knuckle mounted in one of the forked extremities, a disk rotatable upon 90 said journal, and clamping means carried by the other forked extremity and engaging the rocker bar.

2. The combination with a cultivator having a rocker bar, of a plurality of disk supporting arms, each comprising a limb having a recess intermediate its ends, stems 100 slidable in the limb and intersecting the recess and having forked extremities, a turn buckle adjustably engaging the stems for 105 connecting the same, a disk journal having a turning knuckle mounted in one of the forked extremities, a disk rotatable upon said journal, and clamping means carried by the other forked extremity and engaging 110 the rocker bar, an adjustable cap carried by one of the stems and having means engageable with the limb at its outer end for locking said cap against rotation, and coöperative locking projections formed on the cap 115 and the turning knuckle to prevent displacement of the latter.

In testimony whereof I affix my signature in presence of two witnesses.

HENRY BROCKMEYER.

Witnesses:

DANIEL H. ARMSTRONG,
ANDREW J. ZERBE.
